GAS BURNER CONTROL

Edward R. Downe, Shaker Heights, Ohio, assignor to The Bryant Heater Company, Cleveland, Ohio, a corporation of Ohio

Application July 2, 1940, Serial No. 343,611

5 Claims. (Cl. 158—117.1)

This invention relates to improvements in gas burner controls, and has to do primarily with a method and means for providing automatic burner ignition wherein one pilot maintains an igniting flame during off periods of the burner only, while a second pilot operating during the on periods of the burner only performs the usual functions of a safety pilot and serves also to reignite the first pilot at the conclusion of an on period. The two pilots therefore operate alternately and never simultaneously except for a slight overlap sufficient to pass igniting flame from one to the other.

One of the objects of the invention is the provision of a system providing flame ignition wherein the lighting pilot is extinguished during the on periods of the burner, this feature being especially important in lighters for small capacity or broiler burners whereby the effective burner pattern may be affected to a minimum extent by the lighting apparatus.

Another object is the elimination of waste, the lighting pilot flame being of little value during the operation of the burner.

Other objects and features of novelty will appear as I proceed with the description of that embodiment of the invention which, for the purposes of the present application, I have illustrated in the accompanying drawing, in which

Figs. 1 and 2 are diagrammatic illustrations of a burner control embodying the invention, Fig. 1 showing the same in the burner on position, and Fig. 2 in the burner off position.

In the drawing 10 represents a gas burner of conventional character fed by a gas line 11 in which there may be a shut-off valve 12, ordinarily maintained in the open position. A diaphragm valve 13 is interposed in the line between the valve 12 and the burner, this valve comprising a diaphragm 14 forming one side of a pressure chamber 15. When there is line pressure in the chamber 15 the valve is closed, as in Fig. 2, because the area exposed to line pressure on the upper side of the diaphragm is greater than that on the lower side. On the other hand when the pressure above the diaphragm is atmospheric line pressure below the diaphragm raises it and opens the valve, this being a conventional construction.

16 is a conductor which is continuously in communication with line 11 so long as the valve 12 remains open. 17 is a conductor which is continuously in communication with pressure chamber 15. Conductor 17 is in constant communication with a branch 18 leading to a lighting pilot 19. From conductor 16 to branch conductor 20,

20' leads to a control pilot 21. Pilots 19 and 21 are close enough together to enable either one to be ignited by a flame from the other, while pilot 21 at least is mounted in igniting relation with main burner 10. Between conductors 20 and 20' there is a valve of any desired character for controlling the flow of gas to pilot 21. In some cases, as in that herein illustrated, this valve may be an electric valve 22 which may be operated thermostatically, as where the burner is a furnace burner controlled from the premises to be heated. In other cases the valve 22 may be a manual valve, as for example in the case of an oven or broiler burner.

15 On a bracket 23 in which the pilot 21 is supported there is mounted one leg of a thermal element 24 of horseshoe shape, disclosed and claimed in Hahn Patent 2,064,909, which is so disposed as to be heated by flames emerging from holes 25 in the lower portion of the pilot 21. The expansion of element 24 when heated causes the free leg thereof to press against a longitudinally slidable rod 26 that acts upon a ball valve 27 working against a spring 28 that tends to hold the valve away from its seat 29 which is located at the end of a conductor 30 that is in communication with a conductor 16. When valve 27 is open conductor 30 is in free communication through a passage 31 with conductor 18 and thence with conductor 17, as well as with lighting pilot 19.

Diaphragm 14 is held down against its seat during off periods of the burner by line pressure in chamber 15, supplied through conductors 16 and 30, open valve 27, passage 31 and conductors 18 and 17.

40 Means may be provided additionally for supplying pressure to chamber 15 to close the diaphragm valve in the event that some condition in the system calls for the closing of the valve as a safety measure. As illustrative of means for effecting this result I have shown a normally closed valve 32 which, when opened, provides communication between conductors 16 and 17 and thus supplies the necessary gas pressure to chamber 15 for closing the diaphragm valve. The valve 32 may be opened when steam pressure in a steam heating system reaches a predetermined height, when the temperature in a flue reaches a predetermined height, when the temperature of water in a hot water system reaches a predetermined height, etc. When the valve 32 is open the diaphragm valve cannot open, or if it is already open it will then immediately close. Safety devices of this nature are well known in the art.

Fig. 2 of the drawing shows the apparatus in the normal or off condition. Pressure is built up in pressure chamber 15 by gas flowing through conductors 16 and 30 and open valve 27 into conductors 18 and 17. Valve 27 also admits gas to the lighting pilot 19, which is burning. Now if valve 22 is opened flow of gas to control pilot 21 is initiated. This pilot is then ignited from pilot 19 and the flame travels down pilot 21 to the holes 25, the flame from which plays upon the horseshoe 24 and causes it to expand. This expansion moves rod 26 longitudinally to close valve 27 against its seat 29, after which the pressure in chamber 15 and in the conductors 17 and 18 dissipates itself through the lighting pilot 19. Diaphragm valve 13 therefore opens and gas flows to the burner which is ignited by the flame from pilot 21.

When after a period of burner operation the valve 22 is closed, cutting off gas to the pilot 21, thermal element 24 contracts and permits spring 28 to open valve 27, which lets gas into the conductors 18 and 17 and thence into the chamber 15, resulting in the closing of the diaphragm valve 13. Pilot 19 is then relighted by the flame from the residual gas in pilot 21 and conductor 20', after which the latter pilot goes out.

Having thus described my invention, I claim:

1. In apparatus of the class described, a gas supply, a main burner, a main valve adapted to be closed by gas pressure, a lighting pilot and a control pilot arranged in interigniting relation and in igniting relation with the main burner, means for maintaining gas flow to said lighting pilot during off periods of the main burner, means for feeding gas to the control pilot at the beginning of an ignition cycle, and means responsive to the control pilot for relieving the pressure on said main valve and cutting off gas to the lighting pilot, whereby the main burner goes on and the lighting pilot goes off after the control pilot is lighted.

2. In apparatus of the class described, a main burner, a lighting pilot and a control pilot arranged in interigniting relation and in igniting relation with the main burner, means for maintaining gas flow to said lighting pilot during the off periods of the main burner, means for feeding gas to the control pilot at the beginning of an ignition cycle, and means responsive to the control pilot for admitting gas to the main burner

and cutting off gas to the lighting pilot, said last named means acting when the supply of gas to the control pilot alone is terminated to cut off gas to the main burner and admit gas to the lighting pilot to be ignited by the control pilot before the latter is extinguished.

3. In a gas burner control system, a main burner, a lighting pilot and a control pilot arranged in interigniting relation, a valve for the main burner, means enabling pressure in the gas line to close said valve, said means also providing flow of gas to said lighting pilot, valve controlled means for feeding gas to said control pilot, and means responsive to the flame from said control pilot for relieving the pressure at said valve to open the same and for cutting off the supply of gas to said lighting pilot.

4. In a gas burner control system, a main burner, a valve therefor, a lighting pilot and a control pilot arranged in interigniting relation, said control pilot being arranged in igniting relation with said main burner, said main burner valve having a pressure chamber adapted when filled with gas under line pressure to hold the valve closed, said pressure chamber being normally in communication with the gas line and with the said lighting pilot, means for feeding gas from the line to said control pilot, a valve for said last named means, and means responsive to the flame from said control pilot for exhausting gas from said pressure chamber and said lighting pilot.

5. In mechanism of the character described, a main burner, a pressure actuated main valve, a lighting pilot, a control pilot, means functioning during the off periods of the main burner to supply gas to the lighting pilot, means for causing gas to flow to the control pilot at the beginning of a lighting cycle, thermal means functioning in response to the operation of the control pilot to relieve pressure on the main valve for opening the same and at the same time to interrupt the flow of gas to the lighting pilot, whereupon the main burner goes on and the lighting pilot goes off, said thermal means functioning when the supply of gas to the control pilot is interrupted to again admit gas to the lighting pilot and to apply gas pressure to close the main valve.

EDWARD R. DOWNE.
